(57) **ABSTRACT**

The present disclosure discloses a light-emitting diode (LED) lamp and an electronic candle lamp, which comprise a baseplate, a plurality of groups of lamp bodies, a lamp shade and a controlling device. The plurality of groups of lamp bodies are disposed on the baseplate, and each group of the lamp bodies respectively comprises a plurality of LEDs arranged in a matrix form; the lamp shade is disposed on the baseplate and has the plurality of groups of lamp bodies nested therein; and the controlling device is electrically connected to the plurality of groups of lamp bodies to control part of the LEDs in each group of the lamp bodies to emit light so that the electronic candle lamp presents a candlelight effect with flickering flames. The LED lamp and the electronic candle lamp of the present disclosure are electronically controlled to realistically simulate the candlelight effect with flickering flames.

ELECTRONIC CANDLE LAMP AND LIGHT-EMITTING DIODE (LED) LAMP

CROSS REFERENCE TO RELATED APPLICATIONS

This application claims the benefit of China Application No. 201510009697.3, which was filed on Jan. 8, 2015, and is included herein by reference.

FIELD OF THE INVENTION

The present disclosure generally relates to the technical field of lighting, and more particularly, to an electronic candle lamp and a light-emitting diode (LED) lamp.

BACKGROUND OF THE INVENTION

As a kind of novel solid-state light source, light-emitting diodes (LEDs) feature low power consumption, a small volume, a fast respond speed, a long service life, and simple dimming and color modulating operations, and are energy saving and environment friendly. Moreover, they are much better than traditional light sources such as incandescent lamps or fluorescent lamps in terms of production, manufacturing, and usability.

Currently, LEDs have become very popular and are widely used in various lamps (e.g., candlelight lamps). However, light distribution of existing LED candlelight lamps is not particularly designed and the light rays emitted by each portion of the whole lamp are disordered. That is, the whole lamp is only shaped as a candle and can not present a real candlelight effect.

SUMMARY OF THE INVENTION

The primary technical problem to be solved by the present disclosure is to provide a light-emitting diode (LED) lamp and an electronic candle lamp, which are electronically controlled to present a candlelight effect with flickering flames.

To solve the aforesaid technical problem, one technical solution adopted by the present disclosure is to provide a light-emitting diode (LED) lamp, which comprises a baseplate, a plurality of groups of lamp bodies, a lamp shade and a controlling device. The plurality of groups of lamp bodies are disposed on the baseplate, and each group of the lamp bodies respectively comprises a plurality of light-emitting diodes (LEDs) arranged in a matrix; the lamp shade is disposed on the baseplate and has the plurality of groups of lamp bodies nested therein; and the controlling device is electrically connected to the plurality of groups of lamp bodies and is configured to control part of the LEDs in each group of the lamp bodies to emit light so that the electronic candle lamp presents a candlelight effect with flickering flames.

Preferably, the plurality of groups of lamp bodies are arranged about a same center, every two adjacent lamp bodies form a predetermined angle therebetween, and each group of the lamp bodies respectively comprises a circuit board, a first LED matrix and a second LED matrix. The circuit board is disposed vertically on the baseplate; the first LED matrix is disposed on a first surface of the circuit board; and the second LED matrix is disposed on a second surface of the circuit board, and the first surface is opposite to the second surface.

Preferably, the electronic candle lamp comprises three groups of the lamp bodies, and every two adjacent lamp bodies form an angle of 120 degrees therebetween.

Preferably, a first surface of each group of the lamp bodies faces a second surface of an adjacent group of the lamp bodies, and the first LED matrix on the first surface of each group of the lamp bodies and the second LED matrix on the second surface of the adjacent group of the lamp bodies form a light-emitting surface.

10 Preferably, each of the first LED matrix and the second LED matrix on the same light-emitting surface is a 4×16 LED matrix, and the first LED matrix and the second LED matrix together form an 8×16 LED matrix.

Preferably, during the displaying of the electronic candle lamp, an image displayed by each of the light-emitting surfaces at least comprises some or all of the following pictures: a first frame of picture, in which the LEDs of rows

15 6 to 14 in column 3, the LEDs of rows 3 to 15 in columns 4, 5, and the LEDs of rows 5 to 13 in column 6 in the light-emitting surface are lightened; a second frame of picture, in which the LEDs of rows 7 to 13 in column 3, the LEDs of rows 1 to 15 in columns 4, 5, and the LEDs of rows

20 5 to 14 in column 6 in the light-emitting surface are lightened; a third frame of picture, in which the LEDs of rows 6 to 12 in column 3, the LEDs of rows 5 to 15 in column 4, the LEDs of rows 3 to 15 in column 5, the LEDs of rows 3 to 13 in column 6, and the LEDs of rows 6 to 11

25 in column 7 in the light-emitting surface are lightened; a fourth frame of picture, in which the LEDs of rows 6 to 16 in column 4, the LEDs of rows 4 to 16 in column 5, the LEDs of rows 4 to 14 in column 6, and the LEDs of rows

30 5 to 12 in column 7 in the light-emitting surface are lightened; a fifth frame of picture, in which the LEDs of rows 5 to 15 in column 3, the LEDs of rows 5 to 16 in column 4, the LEDs of rows 6 to 16 in column 5, and the LEDs of rows 9 to 14 in column 6 in the light-emitting surface are lightened; a sixth frame of picture, in which the LEDs of rows 13 to 16 in column 3, the LEDs of rows 12

35 to 16 in column 4, the LEDs of rows 11 to 16 in columns 5, 6, and the LEDs of rows 12 to 15 in column 7 in the light-emitting surface are lightened; a seventh frame of picture, in which the LEDs of rows 8 to 16 in columns 4, 5, the LEDs of rows 7 to 15 in column 6, the LEDs of rows 7 to 14 in column 7, and the LEDs of rows 7 to 11 in column

40 8 in the light-emitting surface are lightened; an eighth frame of picture, in which the LEDs of rows 10 to 16 in column 4, the LEDs of rows 8 to 16 in column 5, the LEDs of rows 7 to 16 in column 6, the LEDs of rows 6 to 14 in column 7, and the LEDs of rows 5 to 12 in column 8 in the light-emitting surface are lightened; a ninth frame of picture, in which the LEDs of rows 7 to 16 in column 4, the LEDs of rows 4 to 16 in column 5, the LEDs of rows 3 to 15 in column 6, and the LEDs of rows 3 to 14 in column 7 in the light-emitting surface are lightened; a tenth frame of picture,

45 55 in which the LEDs of rows 10 to 15 in column 4, the LEDs of rows 7 to 15 in column 5, the LEDs of rows 6 to 14 in column 6, the LEDs of rows 3 to 13 in column 7, and the LEDs of rows 3 to 10 in column 8 in the light-emitting surface are lightened; an eleventh frame of picture, in which the LEDs of rows 6 to 15 in column 3, the LEDs of rows 4

50 to 15 in columns 4, 5, and the LEDs of rows 5 to 14 in column 6 in the light-emitting surface are lightened; a twelfth frame of picture, in which the LEDs of rows 8 to 14 in column 3, the LEDs of rows 2 to 15 in columns 4, 5, and the LEDs of rows 4 to 14 in column 6 in the light-emitting surface are lightened; a thirteenth frame of picture, in which the LEDs of rows 4 to 15 in column 3, the LEDs of rows 2

55 to 15 in column 4, the LEDs of rows 3 to 14 in column 5, the LEDs of rows 6 to 13 in column 6, and the LEDs of rows 6 to 12 in column 7 in the light-emitting surface are lightened; a fourteenth frame of picture, in which the LEDs of rows 8 to 16 in column 3, the LEDs of rows 7 to 15 in column 4, the LEDs of rows 6 to 14 in column 5, the LEDs of rows 5 to 13 in column 6, and the LEDs of rows 4 to 12 in column 7 in the light-emitting surface are lightened; a fifteenth frame of picture, in which the LEDs of rows 10 to 16 in column 3, the LEDs of rows 9 to 15 in column 4, the LEDs of rows 8 to 14 in column 5, the LEDs of rows 7 to 13 in column 6, and the LEDs of rows 6 to 11 in column 7 in the light-emitting surface are lightened; a sixteenth frame of picture, in which the LEDs of rows 12 to 16 in column 3, the LEDs of rows 11 to 17 in column 4, the LEDs of rows 10 to 16 in column 5, the LEDs of rows 9 to 15 in column 6, and the LEDs of rows 8 to 14 in column 7 in the light-emitting surface are lightened; a seventeenth frame of picture, in which the LEDs of rows 14 to 18 in column 3, the LEDs of rows 13 to 19 in column 4, the LEDs of rows 12 to 18 in column 5, the LEDs of rows 11 to 17 in column 6, and the LEDs of rows 10 to 16 in column 7 in the light-emitting surface are lightened; an eighteenth frame of picture, in which the LEDs of rows 16 to 22 in column 3, the LEDs of rows 15 to 21 in column 4, the LEDs of rows 14 to 20 in column 5, the LEDs of rows 13 to 19 in column 6, and the LEDs of rows 12 to 18 in column 7 in the light-emitting surface are lightened; a nineteenth frame of picture, in which the LEDs of rows 18 to 24 in column 3, the LEDs of rows 17 to 23 in column 4, the LEDs of rows 16 to 22 in column 5, the LEDs of rows 15 to 21 in column 6, and the LEDs of rows 14 to 20 in column 7 in the light-emitting surface are lightened; a twentieth frame of picture, in which the LEDs of rows 20 to 26 in column 3, the LEDs of rows 19 to 25 in column 4, the LEDs of rows 18 to 24 in column 5, the LEDs of rows 17 to 23 in column 6, and the LEDs of rows 16 to 22 in column 7 in the light-emitting surface are lightened; a twenty-first frame of picture, in which the LEDs of rows 22 to 28 in column 3, the LEDs of rows 21 to 27 in column 4, the LEDs of rows 20 to 26 in column 5, the LEDs of rows 19 to 25 in column 6, and the LEDs of rows 18 to 24 in column 7 in the light-emitting surface are lightened; a twenty-second frame of picture, in which the LEDs of rows 24 to 30 in column 3, the LEDs of rows 23 to 29 in column 4, the LEDs of rows 22 to 28 in column 5, the LEDs of rows 21 to 27 in column 6, and the LEDs of rows 20 to 26 in column 7 in the light-emitting surface are lightened; a twenty-third frame of picture, in which the LEDs of rows 26 to 32 in column 3, the LEDs of rows 25 to 31 in column 4, the LEDs of rows 24 to 30 in column 5, the LEDs of rows 23 to 29 in column 6, and the LEDs of rows 22 to 28 in column 7 in the light-emitting surface are lightened; a twenty-fourth frame of picture, in which the LEDs of rows 28 to 34 in column 3, the LEDs of rows 27 to 33 in column 4, the LEDs of rows 26 to 32 in column 5, the LEDs of rows 25 to 31 in column 6, and the LEDs of rows 24 to 30 in column 7 in the light-emitting surface are lightened; a twenty-fifth frame of picture, in which the LEDs of rows 30 to 36 in column 3, the LEDs of rows 29 to 35 in column 4, the LEDs of rows 28 to 34 in column 5, the LEDs of rows 27 to 33 in column 6, and the LEDs of rows 26 to 32 in column 7 in the light-emitting surface are lightened; a twenty-sixth frame of picture, in which the LEDs of rows 32 to 38 in column 3, the LEDs of rows 31 to 37 in column 4, the LEDs of rows 30 to 36 in column 5, the LEDs of rows 29 to 35 in column 6, and the LEDs of rows 28 to 34 in column 7 in the light-emitting surface are lightened; a twenty-seventh frame of picture, in which the LEDs of rows 34 to 40 in column 3, the LEDs of rows 33 to 39 in column 4, the LEDs of rows 32 to 38 in column 5, the LEDs of rows 31 to 37 in column 6, and the LEDs of rows 30 to 36 in column 7 in the light-emitting surface are lightened; a twenty-eighth frame of picture, in which the LEDs of rows 36 to 42 in column 3, the LEDs of rows 35 to 41 in column 4, the LEDs of rows 34 to 40 in column 5, the LEDs of rows 33 to 39 in column 6, and the LEDs of rows 32 to 38 in column 7 in the light-emitting surface are lightened; a twenty-ninth frame of picture, in which the LEDs of rows 38 to 44 in column 3, the LEDs of rows 37 to 43 in column 4, the LEDs of rows 36 to 42 in column 5, the LEDs of rows 35 to 41 in column 6, and the LEDs of rows 34 to 40 in column 7 in the light-emitting surface are lightened; a thirtieth frame of picture, in which the LEDs of rows 40 to 46 in column 3, the LEDs of rows 39 to 45 in column 4, the LEDs of rows 38 to 44 in column 5, the LEDs of rows 37 to 43 in column 6, and the LEDs of rows 36 to 42 in column 7 in the light-emitting surface are lightened; a thirtieth-first frame of picture, in which the LEDs of rows 42 to 50 in column 3, the LEDs of rows 41 to 49 in column 4, the LEDs of rows 40 to 46 in column 5, the LEDs of rows 39 to 45 in column 6, and the LEDs of rows 38 to 44 in column 7 in the light-emitting surface are lightened; a thirtieth-second frame of picture, in which the LEDs of rows 44 to 52 in column 3, the LEDs of rows 43 to 51 in column 4, the LEDs of rows 42 to 48 in column 5, the LEDs of rows 41 to 47 in column 6, and the LEDs of rows 40 to 46 in column 7 in the light-emitting surface are lightened; a thirtieth-third frame of picture, in which the LEDs of rows 46 to 54 in column 3, the LEDs of rows 45 to 53 in column 4, the LEDs of rows 44 to 50 in column 5, the LEDs of rows 43 to 49 in column 6, and the LEDs of rows 42 to 48 in column 7 in the light-emitting surface are lightened; a thirtieth-fourth frame of picture, in which the LEDs of rows 48 to 56 in column 3, the LEDs of rows 47 to 55 in column 4, the LEDs of rows 46 to 52 in column 5, the LEDs of rows 45 to 51 in column 6, and the LEDs of rows 44 to 50 in column 7 in the light-emitting surface are lightened; a thirtieth-fifth frame of picture, in which the LEDs of rows 50 to 60 in column 3, the LEDs of rows 49 to 59 in column 4, the LEDs of rows 48 to 58 in column 5, the LEDs of rows 47 to 57 in column 6, and the LEDs of rows 46 to 56 in column 7 in the light-emitting surface are lightened; a thirtieth-sixth frame of picture, in which the LEDs of rows 52 to 62 in column 3, the LEDs of rows 51 to 61 in column 4, the LEDs of rows 50 to 60 in column 5, the LEDs of rows 49 to 60 in column 6, and the LEDs of rows 48 to 59 in column 7 in the light-emitting surface are lightened; a thirtieth-seventh frame of picture, in which the LEDs of rows 54 to 64 in column 3, the LEDs of rows 53 to 63 in column 4, the LEDs of rows 52 to 62 in column 5, the LEDs of rows 51 to 62 in column 6, and the LEDs of rows 50 to 62 in column 7 in the light-emitting surface are lightened; a thirtieth-eighth frame of picture, in which the LEDs of rows 56 to 66 in column 3, the LEDs of rows 55 to 65 in column 4, the LEDs of rows 54 to 64 in column 5, the LEDs of rows 53 to 64 in column 6, and the LEDs of rows 52 to 64 in column 7 in the light-emitting surface are lightened; a thirtieth-ninth frame of picture, in which the LEDs of rows 58 to 68 in column 3, the LEDs of rows 57 to 67 in column 4, the LEDs of rows 56 to 66 in column 5, theLEDs of rows 55 to 66 in column 6, and the LEDs of rows 54 to 66 in column 7 in the light-emitting surface are lightened; a thirtieth-tenth frame of picture, in which the LEDs of rows 60 to 70 in column 3, the LEDs of rows 59 to 69 in column 4, the LEDs of rows 58 to 68 in column 5, the LEDs of rows 57 to 68 in column 6, and the LEDs of rows 56 to 68 in column 7 in the light-emitting surface are lightened; a thirtieth-eleventh frame of picture, in which the LEDs of rows 62 to 72 in column 3, the LEDs of rows 61 to 71 in column 4, the LEDs of rows 60 to 70 in column 5, the LEDs of rows 59 to 70 in column 6, and the LEDs of rows 58 to 70 in column 7 in the light-emitting surface are lightened; a thirtieth-twelfth frame of picture, in which the LEDs of rows 64 to 74 in column 3, the LEDs of rows 63 to 73 in column 4, the LEDs of rows 62 to 72 in column 5, the LEDs of rows 61 to 72 in column 6, and the LEDs of rows 60 to 72 in column 7 in the light-emitting surface are lightened; a thirtieth-thirteenth frame of picture, in which the LEDs of rows 66 to 76 in column 3, the LEDs of rows 65 to 75 in column 4, the LEDs of rows 64 to 74 in column 5, the LEDs of rows 63 to 74 in column 6, and the LEDs of rows 62 to 74 in column 7 in the light-emitting surface are lightened; a thirtieth-fourteenth frame of picture, in which the LEDs of rows 68 to 78 in column 3, the LEDs of rows 67 to 77 in column 4, the LEDs of rows 66 to 76 in column 5, the LEDs of rows 65 to 76 in column 6, and the LEDs of rows 64 to 76 in column 7 in the light-emitting surface are lightened; a thirtieth-fifteenth frame of picture, in which the LEDs of rows 70 to 80 in column 3, the LEDs of rows 69 to 79 in column 4, the LEDs of rows 68 to 78 in column 5, the LEDs of rows 67 to 78 in column 6, and the LEDs of rows 66 to 78 in column 7 in the light-emitting surface are lightened; a thirtieth-sixteenth frame of picture, in which the LEDs of rows 72 to 82 in column 3, the LEDs of rows 71 to 81 in column 4, the LEDs of rows 70 to 80 in column 5, the LEDs of rows 69 to 80 in column 6, and the LEDs of rows 68 to 80 in column 7 in the light-emitting surface are lightened; a thirtieth-seventeenth frame of picture, in which the LEDs of rows 74 to 84 in column 3, the LEDs of rows 73 to 83 in column 4, the LEDs of rows 72 to 82 in column 5, the LEDs of rows 71 to 82 in column 6, and the LEDs of rows 70 to 82 in column 7 in the light-emitting surface are lightened; a thirtieth-eighteenth frame of picture, in which the LEDs of rows 76 to 86 in column 3, the LEDs of rows 75 to 85 in column 4, the LEDs of rows 74 to 84 in column 5, the LEDs of rows 73 to 84 in column 6, and the LEDs of rows 72 to 84 in column 7 in the light-emitting surface are lightened; a thirtieth-nineteenth frame of picture, in which the LEDs of rows 78 to 88 in column 3, the LEDs of rows 77 to 87 in column 4, the LEDs of rows 76 to 86 in column 5, the LEDs of rows 75 to 86 in column 6, and the LEDs of rows 74 to 86 in column 7 in the light-emitting surface are lightened; a thirtieth-twentieth frame of picture, in which the LEDs of rows 80 to 90 in column 3, the LEDs of rows 79 to 89 in column 4, the LEDs of rows 78 to 88 in column 5, the LEDs of rows 77 to 88 in column 6, and the LEDs of rows 76 to 88 in column 7 in the light-emitting surface are lightened; a thirtieth-twenty-first frame of picture, in which the LEDs of rows 82 to 92 in column 3, the LEDs of rows 81 to 91 in column 4, the LEDs of rows 80 to 90 in column 5, the LEDs of rows 79 to 90 in column 6, and the LEDs of rows 78 to 90 in column 7 in the light-emitting surface are lightened; a thirtieth-twenty-second frame of picture, in which the LEDs of rows 84 to 94 in column 3, the LEDs of rows 83 to 93 in column 4, the LEDs of rows 82 to 92 in column 5, the LEDs of rows 81 to 92 in column 6, and the LEDs of rows 80 to 92 in column 7 in the light-emitting surface are lightened; a thirtieth-twenty-third frame of picture, in which the LEDs of rows 86 to 96 in column 3, the LEDs of rows 85 to 95 in column 4, the LEDs of rows 84 to 94 in column 5, the LEDs of rows 83 to 94 in column 6, and the LEDs of rows 82 to 94 in column 7 in the light-emitting surface are lightened; a thirtieth-twenty-fourth frame of picture, in which the LEDs of rows 88 to 98 in column 3, the LEDs of rows 87 to 97 in column 4, the LEDs of rows 86 to 96 in column 5, the LEDs of rows 85 to 96 in column 6, and the LEDs of rows 84 to 96 in column 7 in the light-emitting surface are lightened; a thirtieth-twenty-fifth frame of picture, in which the LEDs of rows 90 to 100 in column 3, the LEDs of rows 89 to 99 in column 4, the LEDs of rows 88 to 98 in column 5, the LEDs of rows 87 to 98 in column 6, and the LEDs of rows 86 to 98 in column 7 in the light-emitting surface are lightened; a thirtieth-twenty-sixth frame of picture, in which the LEDs of rows 92 to 102 in column 3, the LEDs of rows 91 to 101 in column 4, the LEDs of rows 90 to 100 in column 5, the LEDs of rows 89 to 100 in column 6, and the LEDs of rows 88 to 100 in column 7 in the light-emitting surface are lightened; a thirtieth-twenty-seventh frame of picture, in which the LEDs of rows 94 to 104 in column 3, the LEDs of rows 93 to 103 in column 4, the LEDs of rows 92 to 102 in column 5, the LEDs of rows 91 to 102 in column 6, and the LEDs of rows 90 to 102 in column 7 in the light-emitting surface are lightened; a thirtieth-twenty-eighth frame of picture, in which the LEDs of rows 96 to 106 in column 3, the LEDs of rows 95 to 105 in column 4, the LEDs of rows 94 to 104 in column 5, the LEDs of rows 93 to 104 in column 6, and the LEDs of rows 92 to 104 in column 7 in the light-emitting surface are lightened; a thirtieth-twenty-ninth frame of picture, in which the LEDs of rows 98 to 108 in column 3, the LEDs of rows 97 to 107 in column 4, the LEDs of rows 96 to 106 in column 5, the LEDs of rows 95 to 106 in column 6, and the LEDs of rows 94 to 106 in column 7 in the light-emitting surface are lightened; a thirtieth-twentieth frame of picture, in which the LEDs of rows 100 to 110 in column 3, the LEDs of rows 99 to 109 in column 4, the LEDs of rows 98 to 108 in column 5, the LEDs of rows 97 to 108 in column 6, and the LEDs of rows 96 to 108 in column 7 in the light-emitting surface are lightened; a thirtieth-twenty-first frame of picture, in which the LEDs of rows 102 to 112 in column 3, the LEDs of rows 101 to 111 in column 4, the LEDs of rows 100 to 110 in column 5, the LEDs of rows 99 to 110 in column 6, and the LEDs of rows 98 to 110 in column 7 in the light-emitting surface are lightened; a thirtieth-twenty-second frame of picture, in which the LEDs of rows 104 to 114 in column 3, the LEDs of rows 103 to 113 in column 4, the LEDs of rows 102 to 112 in column 5, the LEDs of rows 101 to 112 in column 6, and the LEDs of rows 100 to 112 in column 7 in the light-emitting surface are lightened; a thirtieth-twenty-third frame of picture, in which the LEDs of rows 106 to 116 in column 3, the LEDs of rows 105 to 115 in column 4, the LEDs of rows 104 to 114 in column 5, the LEDs of rows 103 to 114 in column 6, and the LEDs of rows 102 to 114 in column 7 in the light-emitting surface are lightened; a thirtieth-twenty-fourth frame of picture, in which the LEDs of rows 108 to 118 in column 3, the LEDs of rows 107 to 117 in column 4, the LEDs of rows 106 to 116 in column 5, the LEDs of rows 105 to 116 in column 6, and the LEDs of rows 104 to 116 in column 7 in the light-emitting surface are lightened; a thirtieth-twenty-fifth frame of picture, in which the LEDs of rows 110 to 120 in column 3, the LEDs of rows 109 to 119 in column 4, the LEDs of rows 108 to 118 in column 5, the LEDs of rows 107 to 118 in column 6, and the LEDs of rows 106 to 118 in column 7 in the light-emitting surface are lightened; a thirtieth-twenty-sixth frame of picture, in which the LEDs of rows 112 to 122 in column 3, the LEDs of rows 111 to 121 in column 4, the LEDs of rows 110 to 120 in column 5, the LEDs of rows 109 to 120 in column 6, and the LEDs of rows 108 to 120 in column 7 in the light-emitting surface are lightened; a thirtieth-twenty-seventh frame of picture, in which the LEDs of rows 114 to 124 in column 3, the LEDs of rows 113 to 123 in column 4, the LEDs of rows 112 to 122 in column 5, the LEDs of rows 111 to 122 in column 6, and the LEDs of rows 110 to 122 in column 7 in the light-emitting surface are lightened; a thirtieth-twenty-eighth frame of picture, in which the LEDs of rows 116 to 126 in column 3, the LEDs of rows 115 to 125 in column 4, the LEDs of rows 114 to 124 in column 5, the LEDs of rows 113 to 124 in column 6, and the LEDs of rows 112 to 124 in column 7 in the light-emitting surface are lightened; a thirtieth-twenty-ninth frame of picture, in which the LEDs of rows 118 to 128 in column 3, the LEDs of rows 117 to 127 in column 4, the LEDs of rows 116 to 126 in column 5, the LEDs of rows 115 to 126 in column 6, and the LEDs of rows 114 to 126 in column 7 in the light-emitting surface are lightened; a thirtieth-twentieth frame of picture, in which the LEDs of rows 120 to 130 in column 3, the LEDs of rows 119 to 129 in column 4, the LEDs of rows 118 to 128 in column 5, the LEDs of rows 117 to 128 in column 6, and the LEDs of rows 116 to 128 in column 7 in the light-emitting surface are lightened; a thirtieth-twenty-first frame of picture, in which the LEDs of rows 122 to 132 in column 3, the LEDs of rows 121 to 131 in column 4, the LEDs of rows 120 to 130 in column 5, the LEDs of rows 119 to 130 in column 6, and the LEDs of rows 118 to 130 in column 7 in the light-emitting surface are lightened; a thirtieth-twenty-second frame of picture, in which the LEDs of rows 124 to 134 in column 3, the LEDs of rows 123 to 133 in column 4, the LEDs of rows 122 to 132 in column 5, the LEDs of rows 121 to 132 in column 6, and the LEDs of rows 120 to 132 in column 7 in the light-emitting surface are lightened; a thirtieth-twenty-third frame of picture, in which the LEDs of rows 126 to 136 in column 3, the LEDs of rows 125 to 135 in column 4, the LEDs of rows 124 to 134 in column 5, the LEDs of rows 123 to 134 in column 6, and the LEDs of rows 122 to 134 in column 7 in the light-emitting surface are lightened; a thirtieth-twenty-fourth frame of picture, in which the LEDs of rows 128 to 138 in column 3, the LEDs of rows 127 to 137 in column 4, the LEDs of rows 126 to 136 in column 5, the LEDs of rows 125 to 136 in column 6, and the LEDs of rows 124 to 136 in column 7 in the light-emitting surface are lightened; a thirtieth-twenty-fifth frame of picture, in which the LEDs of rows 130 to 140 in column 3, the LEDs of rows 129 to 139 in column 4, the LEDs of rows 128 to 138 in column 5, the LEDs of rows 127 to 138 in column 6, and the LEDs of rows 126 to 138 in column 7 in the light-emitting surface are lightened; a thirtieth-twenty-sixth frame of picture, in which the LEDs of rows 132 to 142 in column 3, the LEDs of rows 131 to 141 in column 4, the LEDs of rows 130 to 140 in column 5, the LEDs of rows 129 to 140 in column 6, and the LEDs of rows 128 to 140 in column 7 in the light-emitting surface are lightened; a thirtieth-twenty-seventh frame of picture, in which the LEDs of rows 134 to 144 in column 3, the LEDs of rows 133 to 143 in column 4, the LEDs of rows 132 to 142 in column 5, the LEDs of rows 131 to 142 in column 6, and the LEDs of rows 130 to 142 in column 7 in the light-emitting surface are lightened; a thirtieth-twenty-eighth frame of picture, in which the LEDs of rows 136 to 146 in column 3, the LEDs of rows 135 to 145 in column 4, the LEDs of rows 134 to 144 in column 5, the LEDs of rows 133 to 144 in column 6, and the LEDs of rows 132 to 144 in column 7 in the light-emitting surface are lightened; a thirtieth-twenty-ninth frame of picture, in which the LEDs of rows 138 to 148 in column 3, the LEDs of rows 137 to 147 in column 4, the LEDs of rows 136 to 146 in column 5, the LEDs of rows 135 to 146 in column 6, and the LEDs of rows 134 to 146 in column 7 in the light-emitting surface are lightened; a thirtieth-twentieth frame of picture, in which the LEDs of rows 140 to 150 in column 3, the LEDs of rows 139 to 149 in column 4, the LEDs of rows 138 to 148 in column 5, the LEDs of rows 137 to 148 in column 6, and the LEDs of rows 136 to 148 in column 7 in the light-emitting surface are lightened; a thirtieth-twenty-first frame of picture, in which the LEDs of rows 142 to 152 in column 3, the LEDs of rows 141 to 151 in column 4, the LEDs of rows 140 to 150 in column 5, the LEDs of rows 139 to 150 in column 6, and the LEDs of rows 138 to 150 in column 7 in the light-emitting surface are lightened; a thirtieth-twenty-second frame of picture, in which the LEDs of rows 144 to 154 in column 3, the LEDs of rows 143 to 153 in column 4, the LEDs of rows 142 to 152 in column 5, the LEDs of rows 141 to 152 in column 6, and the LEDs of rows 140 to 152 in column 7 in the light-emitting surface are lightened; a thirtieth-twenty-third frame of picture, in which the LEDs of rows 146 to 156 in column 3, the LEDs of rows 145 to 155 in column 4, the LEDs of rows 144 to 154 in column 5, the LEDs of rows 143 to 154 in column 6, and the LEDs of rows 142 to 154 in column 7 in the light-emitting surface are lightened; a thirtieth-twenty-fourth frame of picture, in which the LEDs of rows 148 to 158 in column 3, the LEDs of rows 147 to 157 in column 4, the LEDs of rows 146 to 156 in column 5, the LEDs of rows 145 to 156 in column 6, and the LEDs of rows 144 to 156 in column 7 in the light-emitting surface are lightened; a thirtieth-twenty-fifth frame of picture, in which the LEDs of rows 150 to 160 in column 3, the LEDs of rows 149 to 159 in column 4, the LEDs of rows 148 to 158 in column 5, the LEDs of rows 147 to 158 in column 6, and the LEDs of rows 146 to 158 in column 7 in the light-emitting surface are lightened; a thirtieth-twenty-sixth frame of picture, in which the LEDs of rows 152 to 162 in column 3, the LEDs of rows 151 to 161 in column 4, the LEDs of rows 150 to 160 in column 5, the LEDs of rows 149 to 160 in column 6, and the LEDs of rows 148 to 160 in column 7 in the light-emitting surface are lightened; a thirtieth-twenty-seventh frame of picture, in which the LEDs of rows 154 to 164 in column 3, the LEDs of rows 153 to 163 in column 4, the LEDs of rows 152 to 162 in column 5, the LEDs of rows 151 to 162 in column 6, and the LEDs of rows 150 to 162 in column 7 in the light-emitting surface are lightened; a thirtieth-twenty-eighth frame of picture, in which the LEDs of rows 156 to 166 in column 3, the LEDs of rows 155 to 165 in column 4, the LEDs of rows 154 to 164 in column 5, the LEDs of rows 153 to 164 in column 6, and the LEDs of rows 152 to 164 in column 7 in the light-emitting surface are lightened; a thirtieth-twenty-ninth frame of picture, in which the LEDs of rows 158 to 168 in column 3, the LEDs of rows 157 to 167 in column 4, the LEDs of rows 156 to 166 in column 5, the LEDs of rows 155 to 166 in column 6, and the LEDs of rows 154 to 166 in column 7 in the light-emitting surface are lightened; a thirtieth-twentieth frame of picture, in which the LEDs of rows 160 to 170 in column 3, the LEDs of rows 159 to 169 in column 4, the LEDs of rows 158 to 168 in column 5, the LEDs of rows 157 to 168 in column 6, and the LEDs of rows 156 to 168 in column 7 in the light-emitting surface are lightened; a thirtieth-twenty-first frame of picture, in which the LEDs of rows 162 to 172 in column 3, the LEDs of rows 161 to 171 in column 4, the LEDs of rows 160 to 170 in column 5, the LEDs of rows 159 to 170 in column 6, and the LEDs of rows 158 to 170 in column 7 in the light-emitting surface are lightened; a thirtieth-twenty-second frame of picture, in which the LEDs of rows 164 to 174 in column 3, the LEDs of rows 163 to 173 in column 4, the LEDs of rows 162 to 172 in column 5, the LEDs of rows 161 to 172 in column 6, and the LEDs of rows 160 to 172 in column 7 in the light-emitting surface are lightened; a thirtieth-twenty-third frame of picture, in which the LEDs of rows 166 to 176 in column 3, the LEDs of rows 165 to 175 in column 4, the LEDs of rows 164 to 174 in column 5, the LEDs of rows 163 to 174 in column 6, and the LEDs of rows 162 to 174 in column 7 in the light

to 16 in columns 4, 5, and the LEDs of rows 6 to 13 in column 6 in the light-emitting surface are lightened; a fourteenth frame of picture, in which the LEDs of rows 5 to 8 in column 1, the LEDs of rows 4 to 12 in column 2, the LEDs of rows 4 to 15 in column 3, the LEDs of rows 1 to 15 in columns 4, 5, and the LEDs of rows 2 to 10 in column 6 in the light-emitting surface are lightened; a fifteenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened; a sixteenth frame of picture, in which the LEDs of rows 2 to 7 in column 1, the LEDs of rows 3 to 13 in column 2, the LEDs of rows 4 to 15 in column 3, the LEDs of rows 6 to 15 in column 4, and the LEDs of rows 10 to 14 in column 5 in the light-emitting surface are lightened; a seventeenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened; an eighteenth frame of picture, in which the LEDs of rows 7 to 15 in column 3, the LEDs of rows 4 to 16 in column 4, the LEDs of rows 3 to 16 in column 5, the LEDs of rows 3 to 13 in column 6, and the LEDs of rows 4 to 10 in column 7 in the light-emitting surface are lightened; a nineteenth frame of picture, in which the LEDs of rows 5 to 14 in column 3, the LEDs of rows 1 to 15 in columns 4, 5, and the LEDs of rows 5 to 13 in column 6 in the light-emitting surface are lightened; a twentieth frame of picture, in which the LEDs of rows 6 to 14 in column 3, the LEDs of rows 5 to 15 in column 4, the LEDs of rows 4 to 15 in column 5, and the LEDs of rows 5 to 14 in column 6 in the light-emitting surface are lightened; a twenty-first frame of picture, in which the LEDs of rows 6 to 16 in column 4, the LEDs of rows 4 to 16 in column 5, and the LEDs of rows 4 to 15 in column 6 in the light-emitting surface are lightened; a twenty-second frame of picture, in which the LEDs of rows 11 to 16 in column 4, the LEDs of rows 8 to 16 in column 5, the LEDs of rows 6 to 15 in column 6, the LEDs of rows 5 to 14 in column 7, and the LEDs of rows 4 to 12 in column 8 in the light-emitting surface are lightened; a twenty-third frame of picture, in which the LEDs of rows 10 to 16 in column 4, the LEDs of rows 9 to 16 in column 5, the LEDs of rows 8 to 15 in column 6, the LEDs of rows 8 to 13 in column 7, and the LEDs of rows 9 to 12 in column 8 in the light-emitting surface are lightened; a twenty-fourth frame of picture, in which the LEDs of rows 6 to 10 in column 1, the LEDs of rows 6 to 13 in column 2, the LEDs of rows 7 to 16 in columns 3, 4, the LEDs of rows 9 to 16 in column 5, and the LEDs of rows 10 to 16 in column 6 in the light-emitting surface are lightened; and a twenty-fifth frame of picture, in which the LEDs of rows 5 to 15 in column 3, the LEDs of rows 4 to 16 in column 4, the LEDs of rows 5 to 16 in column 5, and the LEDs of rows 6 to 14 in column 6 in the light-emitting surface are lightened.

Preferably, each light-emitting surface circularly displays the first frame of picture to the twenty-fifth frame of picture in sequence so that the electronic candle lamp dynamically displays the candlelight effect with flickering flames.

Preferably, each of the first frame of picture to the twenty-fifth frame of picture is displayed for 100~150 ms.

Preferably, the controlling device comprises a controller and a plurality of controlling circuits, the controller is electrically connected to the plurality of controlling circuits to input instructions to each of the controlling circuits, and each of the controlling circuits is electrically connected to

the first LED matrix and the second LED matrix on a corresponding group of the lamp bodies, or connected to the first LED matrix and the second LED matrix on a same light-emitting surface to control the LEDs on each group of the lamp bodies or on each of the light-emitting surfaces so that the electronic candle lamp displays the candlelight effect with flickering flames.

To solve the aforesaid technical problem, another technical solution adopted by the present disclosure is to provide 10 a light-emitting diode (LED) lamp, which comprises a baseplate, a plurality of groups of lamp bodies, a lamp shade and a controlling device. The plurality of groups of lamp bodies are disposed on the baseplate, each group of the lamp bodies respectively comprises a plurality of LEDs arranged 15 in a matrix, the plurality of groups of lamp bodies are arranged about a same center, and every two adjacent lamp bodies form a predetermined angle therebetween; the lamp shade is disposed on the baseplate and has the plurality of groups of lamp bodies nested therein; and the controlling device is electrically connected to the plurality of groups of lamp bodies to control part of the LEDs in each group of the lamp bodies to emit light so that the LED lamp presents light-emitting effects of various forms.

Preferably, each group of the lamp bodies respectively 25 comprises a circuit board, a first LED matrix and a second LED matrix. The circuit board is disposed vertically on the baseplate; the first LED matrix is disposed on a first surface of the circuit board; and the second LED matrix is disposed on a second surface of the circuit board, and the first surface 30 is opposite to the second surface. A first surface of each group of the lamp bodies faces a second surface of an adjacent group of the lamp bodies, and the first LED matrix on the first surface of each group of the lamp bodies and the second LED matrix on the second surface of the adjacent group of the lamp bodies form a light-emitting surface.

Preferably, the LEDs in both the first LED matrix and the second LED matrix of each group of the lamp bodies are LED chips, and the LED chips in the first LED matrix and/or the second LED matrix are integrally encapsulated on the 40 first surface and/or the second surface.

Preferably, the LED lamp presents a candlelight effect with flickering flames.

Preferably, each of the first LED matrix and the second 45 LED matrix on the same light-emitting surface is a 4×16 LED matrix, and the first LED matrix and the second LED matrix together form an 8×16 LED matrix. During the displaying of the LED lamp, an image displayed by each of the light-emitting surfaces at least comprises some or all of the following pictures: a first frame of picture, in which the 50 LEDs of rows 6 to 14 in column 3, the LEDs of rows 3 to 15 in columns 4, 5, and the LEDs of rows 5 to 13 in column 6 in the light-emitting surface are lightened; a second frame of picture, in which the LEDs of rows 7 to 13 in column 3, the LEDs of rows 1 to 15 in columns 4, 5, and the LEDs of 55 rows 5 to 14 in column 6 in the light-emitting surface are lightened; a third frame of picture, in which the LEDs of rows 6 to 12 in column 3, the LEDs of rows 5 to 15 in column 4, the LEDs of rows 3 to 15 in column 5, the LEDs of rows 3 to 13 in column 6, and the LEDs of rows 6 to 11 60 in column 7 in the light-emitting surface are lightened; a fourth frame of picture, in which the LEDs of rows 6 to 16 in column 4, the LEDs of rows 4 to 16 in column 5, the LEDs of rows 4 to 14 in column 6, and the LEDs of rows 5 to 12 in column 7 in the light-emitting surface are lightened; a fifth frame of picture, in which the LEDs of rows 5 to 15 in column 3, the LEDs of rows 5 to 16 in column 4, the LEDs of rows 6 to 16 in column 5, and the

LEDs of rows 9 to 14 in column 6 in the light-emitting surface are lightened; a sixth frame of picture, in which the LEDs of rows 13 to 16 in column 3, the LEDs of rows 12 to 16 in column 4, the LEDs of rows 11 to 16 in columns 5, 6, and the LEDs of rows 12 to 15 in column 7 in the light-emitting surface are lightened; a seventh frame of picture, in which the LEDs of rows 8 to 16 in columns 4, 5, the LEDs of rows 7 to 15 in column 6, the LEDs of rows 7 to 14 in column 7, and the LEDs of rows 7 to 11 in column 8 in the light-emitting surface are lightened; an eighth frame of picture, in which the LEDs of rows 10 to 16 in column 4, the LEDs of rows 8 to 16 in column 5, the LEDs of rows 7 to 16 in column 6, the LEDs of rows 6 to 14 in column 7, and the LEDs of rows 5 to 12 in column 8 in the light-emitting surface are lightened; a ninth frame of picture, in which the LEDs of rows 7 to 16 in column 4, the LEDs of rows 4 to 16 in column 5, the LEDs of rows 3 to 15 in column 6, and the LEDs of rows 3 to 14 in column 7 in the light-emitting surface are lightened; a tenth frame of picture, in which the LEDs of rows 10 to 15 in column 4, the LEDs of rows 7 to 15 in column 5, the LEDs of rows 6 to 14 in column 6, the LEDs of rows 3 to 13 in column 7, and the LEDs of rows 3 to 10 in column 8 in the light-emitting surface are lightened; an eleventh frame of picture, in which the LEDs of rows 6 to 15 in column 3, the LEDs of rows 4 to 15 in columns 4, 5, and the LEDs of rows 5 to 14 in column 6 in the light-emitting surface are lightened; a twelfth frame of picture, in which the LEDs of rows 8 to 14 in column 3, the LEDs of rows 2 to 15 in columns 4, 5, and the LEDs of rows 4 to 14 in column 6 in the light-emitting surface are lightened; a thirteenth frame of picture, in which the LEDs of rows 4 to 15 in column 3, the LEDs of rows 2 to 16 in columns 4, 5, and the LEDs of rows 6 to 13 in column 6 in the light-emitting surface are lightened; a fourteenth frame of picture, in which the LEDs of rows 5 to 8 in column 1, the LEDs of rows 4 to 12 in column 2, the LEDs of rows 4 to 15 in column 3, the LEDs of rows 1 to 15 in columns 4, 5, and the LEDs of rows 2 to 10 in column 6 in the light-emitting surface are lightened; a fifteenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened; a sixteenth frame of picture, in which the LEDs of rows 2 to 7 in column 1, the LEDs of rows 3 to 13 in column 2, the LEDs of rows 4 to 15 in column 3, the LEDs of rows 6 to 15 in column 4, and the LEDs of rows 10 to 14 in column 5 in the light-emitting surface are lightened; a seventeenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened; an eighteenth frame of picture, in which the LEDs of rows 7 to 15 in column 3, the LEDs of rows 4 to 16 in column 4, the LEDs of rows 3 to 16 in column 5, the LEDs of rows 3 to 13 in column 6, and the LEDs of rows 4 to 10 in column 7 in the light-emitting surface are lightened; a nineteenth frame of picture, in which the LEDs of rows 5 to 14 in column 3, the LEDs of rows 1 to 15 in columns 4, 5, and the LEDs of rows 5 to 13 in column 6 in the light-emitting surface are lightened; a twentieth frame of picture, in which the LEDs of rows 6 to 14 in column 3, the LEDs of rows 5 to 15 in column 4, the LEDs of rows 4 to 15 in column 5, and the LEDs of rows 5 to 14 in column 6 in the light-emitting surface are lightened; a twenty-first frame of picture, in which the LEDs of rows 6 to 16 in column 4, the LEDs of rows 4 to 16 in column 5, and the LEDs of rows 4 to 16 in column 6 in the light-emitting surface are lightened; a twenty-second frame of picture, in which the LEDs of rows 11 to 16 in column 4, the LEDs of rows 8 to 16 in column 5, the LEDs of rows 6 to 15 in column 6, the LEDs of rows 5 to 14 in column 7, and the LEDs of rows 4 to 12 in column 8 in the light-emitting surface are lightened; a twenty-third frame of picture, in which the LEDs of rows 10 to 16 in column 4, the LEDs of rows 9 to 16 in column 5, the LEDs of rows 8 to 15 in column 6, the LEDs of rows 7 to 12 in column 8 in the light-emitting surface are lightened; a twenty-fourth frame of picture, in which the LEDs of rows 6 to 10 in column 1, the LEDs of rows 6 to 13 in column 2, the LEDs of rows 7 to 16 in columns 3, 4, the LEDs of rows 9 to 16 in column 5, and the LEDs of rows 10 to 16 in column 6 in the light-emitting surface are lightened; and a twenty-fifth frame of picture, in which the LEDs of rows 5 to 15 in column 3, the LEDs of rows 4 to 16 in column 4, the LEDs of rows 5 to 16 in column 5, and the LEDs of rows 6 to 14 in column 6 in the light-emitting surface are lightened.

4 to 15 in column 6 in the light-emitting surface are lightened; a twenty-second frame of picture, in which the LEDs of rows 11 to 16 in column 4, the LEDs of rows 8 to 16 in column 5, the LEDs of rows 6 to 15 in column 6, the LEDs of rows 5 to 14 in column 7, and the LEDs of rows 4 to 12 in column 8 in the light-emitting surface are lightened; a twenty-third frame of picture, in which the LEDs of rows 10 to 16 in column 4, the LEDs of rows 9 to 16 in column 5, the LEDs of rows 8 to 15 in column 6, the LEDs of rows 8 to 13 in column 7, and the LEDs of rows 9 to 12 in column 8 in the light-emitting surface are lightened; a twenty-fourth frame of picture, in which the LEDs of rows 6 to 10 in column 1, the LEDs of rows 6 to 13 in column 2, the LEDs of rows 7 to 16 in columns 3, 4, the LEDs of rows 9 to 16 in column 5, and the LEDs of rows 10 to 16 in column 6 in the light-emitting surface are lightened; and a twenty-fifth frame of picture, in which the LEDs of rows 5 to 15 in column 3, the LEDs of rows 4 to 16 in column 4, the LEDs of rows 5 to 16 in column 5, and the LEDs of rows 6 to 14 in column 6 in the light-emitting surface are lightened.

As compared to the prior art, the present disclosure has the following benefits: the LED lamp and the electronic candle lamp of the present disclosure electronically control the LEDs in the plurality of groups of lamp bodies to present the candlelight effect with flickering flames, so a realistic simulation effect is provided; and furthermore, the present disclosure adopts LEDs to replace the traditional candles to emit light, so the lamps of the present disclosure are environment friendly and durable and have a great market.

BRIEF DESCRIPTION OF THE DRAWINGS

FIG. 1 is a schematic perspective view of a light-emitting diode (LED) lamp according to an embodiment of the present disclosure;

FIG. 2 is a schematic exploded view of the LED shown in FIG. 1;

FIG. 3 is a partially enlarged schematic view of the LED shown in FIG. 2;

FIG. 4 is a schematic circuit diagram of the LED lamp shown in FIG. 1;

FIG. 5 is a schematic view illustrating the connection between a controlling circuit and a first LED matrix as well as a second LED matrix; and

FIG. 6A shows a first frame of picture displayed by the LED lamp of FIG. 1.

FIG. 6B shows a second frame of picture displayed by the LED lamp of FIG. 1.

FIG. 6C shows a third frame of picture displayed by the LED lamp of FIG. 1.

FIG. 6D shows a fourth frame of picture displayed by the LED lamp of FIG. 1.

FIG. 6E shows a fifth frame of picture displayed by the LED lamp of FIG. 1.

FIG. 6F shows a sixth frame of picture displayed by the LED lamp of FIG. 1.

FIG. 6G shows a seventh frame of picture displayed by the LED lamp of FIG. 1.

FIG. 6H shows an eighth frame of picture displayed by the LED lamp of FIG. 1.

FIG. 6W shows a twenty-third frame of picture displayed by the LED lamp of FIG. 1.

FIG. 6X shows a twenty-fourth frame of picture displayed by the LED lamp of FIG. 1.

FIG. 6Y shows a twenty-fifth frame of picture displayed by the LED lamp of FIG. 1.

DETAILED DESCRIPTION OF THE INVENTION

Hereinafter, the present disclosure will be described in detail with reference to the attached drawings and embodiments thereof.

Referring to FIG. 1 to FIG. 3 together, FIG. 1 is a schematic perspective view of a light-emitting diode (LED) lamp according to an embodiment of the present disclosure; FIG. 2 is a schematic exploded view of the LED shown in FIG. 1; and FIG. 3 is a partially enlarged schematic view of the LED shown in FIG. 2. As shown in FIG. 1 to FIG. 3, an LED lamp 100 of the present disclosure comprises a baseplate 110, a plurality of groups of lamp bodies 120, a lamp shade 130 and a controlling device 140.

The plurality of groups of lamp bodies 120 is disposed on the baseplate 110, each group of the lamp bodies 120 respectively comprises a plurality of light-emitting diodes (LEDs) 121 arranged in a matrix form, the plurality of groups of lamp bodies 120 are arranged about a same center, and every two adjacent lamp bodies 120 form a predetermined angle therebetween.

The lamp shade 130 is disposed on the baseplate 110 and has the plurality of groups of lamp bodies 120 nested therein, and the lamp shade 130 may be made of a transparent material.

The controlling device 140 is electrically connected to the plurality of groups of lamp bodies 120 to control part of the LEDs 121 in each group of the lamp bodies 120 to emit light so that the whole LED lamp 100 can present light-emitting effects of various forms.

In embodiments of the present disclosure, the LED lamp 100 can present the candlelight effect with flickering flames; that is, the LED lamp 100 of the present disclosure is used as an electronic candle lamp. Preferably, the baseplate 110 is disc-shaped, and the lamp shade 130 is cylinder-shaped. Of course, as will be appreciated by those skilled in the art, the

baseplate 110 and the lamp shade 130 may also be of other different shapes depending on practical needs.

Each group of the lamp bodies 120 comprises a circuit board 122, a first LED matrix 123 and a second LED matrix 124. The circuit board 122 is disposed on the baseplate 110, the first LED matrix 123 is disposed on a first surface 1221 of the circuit board 122, the second LED matrix 124 is disposed on a second surface 1222 of the circuit board 122, and the first surface 1221 is opposite to the second surface 1222.

Preferably, three groups of lamp bodies 120 are taken as an example to introduce the present disclosure in this embodiment, with every two adjacent lamp bodies 120 forming an angle of 120 degrees therebetween. Of course, as will be appreciated by those skilled in the art, the LED lamp and the electronic candle lamp of the present disclosure may also comprise more groups of lamp bodies, with every two adjacent lamp bodies forming a predetermined angle therbetween. Preferably, the larger the volume of the LED lamp or the electronic candle lamp is, the more the lamp bodies used in the LED lamp or the electronic candle lamp will be.

Moreover, as shown in FIG. 2 and FIG. 3, the first surface 1221 of each group of the lamp bodies 120 faces the second surface 1222 of an adjacent group of the lamp bodies 120, and the first LED matrix 123 on the first surface 1221 of each group of the lamp bodies 120 and the second LED matrix 124 on the second surface 1222 of the adjacent group of the lamp bodies 120 form a light-emitting surface. In this embodiment, three different light-emitting surfaces are formed by the three groups of lamp bodies 120, and each of the light-emitting surfaces is sector-shaped with an angle of 120 degrees.

Referring to FIG. 4 together, FIG. 4 is a schematic circuit diagram of the LED lamp 100 shown in FIG. 1. As shown in FIG. 4, the controlling device 140 of the present disclosure comprises a controller 141 and a plurality of controlling circuits 142. The controller 141 is electrically connected to the plurality of controlling circuits 142 respectively to input instructions to each of the controlling circuits 142, and each of the controlling circuits 142 is electrically connected to the first LED matrix 123 and the second LED matrix 124 on a corresponding group of the lamp bodies 120, or connected to the first LED matrix 123 and the second LED matrix 124 on a same light-emitting surface to control the LEDs on each group of the lamp bodies 120 or on each of the light-emitting surfaces.

Preferably, the controller 141 adopts a micro control unit (MCU), and each of the controlling circuits 142 adopts an SN3731 controlling chip with a register disposed therein to store controlling instructions transmitted from the controller 141 and transmit, according to the controlling instructions, corresponding controlling signals to each group of lamp bodies 120 or to the first LED matrix 123 and the second LED matrix 124 on a same light-emitting surface so as to turn on part of the LEDs in the first LED matrix 123 and the second LED matrix 124. Thus, the LED lamp 100 can present the candlelight effect with flickering flames. Of course, as will be appreciated by those skilled in the art, the controller 141 and the controlling circuits 142 may also adopt other types of controlling chips.

Referring to FIG. 5 together, FIG. 5 is a schematic view illustrating the connection between a controlling circuit and a first LED matrix as well as a second LED matrix. In this embodiment, the first LED matrix 123 and the second LED matrix 124 on a same light-emitting surface are taken as an example to introduce the present disclosure, and the controlling chip 142 adopts an SN3731 controlling chip.

The SN3731 controlling chip can control 144 LEDs (i.e., a 9×16 LED matrix) at most. Thus, in this embodiment, each of the first LED matrix **123** and the second LED matrix **124** is preferably a 4×16 LED matrix, so the first LED matrix **123** and the second LED matrix **124** form an 8×16 LED matrix on a same light-emitting surface. Of course, as will be appreciated by those skilled in the art, the first LED matrix **123** and the second LED matrix **124** may also be other kinds of LED matrixes, e.g., one is a 5×16 LED matrix, and the other is a 4×16 LED matrix, and so on.

Preferably, the connection between the SN3731 controlling chip **142** and the first LED matrix **123** as well as the second LED matrix **124** is as shown in FIG. 3. Of course, as will be appreciated by those skilled in the art, no specific limitation is made to the connection between the SN3731 controlling chip **142** and the first LED matrix **123** as well as the second LED matrix **124** in the present disclosure as long as any LED in the first LED matrix **123** and the second LED matrix **124** can be controlled by the SN3731 controlling chip **142** to be turned on or turned off.

In the present disclosure, each of the LEDs in the first LED matrix **123** and the second LED matrix **124** may be an LED that has already been encapsulated. Alternatively, each of the LEDs in the first LED matrix **123** and the second LED matrix **124** is an LED chip that has not been encapsulated, and instead, the LED chips in the first LED matrix **123** are integrally encapsulated on the first surface **1221** of the circuit board **122**, and the LED chips in the second LED matrix **124** are integrally encapsulated on the second surface **1222** of the circuit board **122**; or, each of the LEDs in the first LED matrix **123** and the second LED matrix **124** is an LED chip that is not encapsulated, and the lamp shade **130** and the baseplate **110** are used as an encapsulating body to integrally encapsulate the LED chips on the plurality of groups of lamp bodies **120** therein.

Moreover, further referring to FIGS. 6A to 6Y, FIGS. 6A to 6Y show pictures displayed by the LED lamp **100** of FIG. 1. During the displaying of the LED lamp **100** when being used as an electronic candle lamp, an image displayed by each of the light-emitting surfaces at least comprises some or all of the following pictures:

a first frame of picture, as shown in FIG. 6A, in which the LEDs of rows **6** to **14** in column **3**, the LEDs of rows **3** to **15** in columns **4**, **5**, and the LEDs of rows **5** to **13** in column **6** in the LED matrix (i.e., the 8×16 LED matrix formed by the first 4×16 LED matrix and the second 4×16 LED matrix) of the light-emitting surface are lightened;

a second frame of picture, as shown in FIG. 6B, in which the LEDs of rows **7** to **13** in column **3**, the LEDs of rows **1** to **15** in columns **4**, **5**, and the LEDs of rows **5** to **14** in column **6** in the LED matrix of the light-emitting surface are lightened;

a third frame of picture, as shown in FIG. 6C, in which the LEDs of rows **6** to **12** in column **3**, the LEDs of rows **5** to **15** in column **4**, the LEDs of rows **3** to **15** in column **5**, the LEDs of rows **3** to **13** in column **6**, and the LEDs of rows **6** to **11** in column **7** in the LED matrix of the light-emitting surface are lightened;

a fourth frame of picture, as shown in FIG. 6D, in which the LEDs of rows **6** to **16** in column **4**, the LEDs of rows **4** to **16** in column **5**, the LEDs of rows **4** to **14** in column **6**, and the LEDs of rows **5** to **12** in column **7** in the LED matrix of the light-emitting surface are lightened;

a fifth frame of picture, as shown in FIG. 6E, in which the LEDs of rows **5** to **15** in column **3**, the LEDs of rows **5** to **16** in column **4**, the LEDs of rows **6** to **16** in column **5**, and

the LEDs of rows **9** to **14** in column **6** in the LED matrix of the light-emitting surface are lightened;

a sixth frame of picture, as shown in FIG. 6F, in which the LEDs of rows **13** to **16** in column **3**, the LEDs of rows **12** to **16** in column **4**, the LEDs of rows **11** to **16** in columns **5**, **6**, and the LEDs of rows **12** to **15** in column **7** in the LED matrix of the light-emitting surface are lightened;

a seventh frame of picture, as shown in FIG. 6G, in which the LEDs of rows **8** to **16** in columns **4**, **5**, the LEDs of rows **7** to **15** in column **6**, the LEDs of rows **7** to **14** in column **7**, and the LEDs of rows **7** to **11** in column **8** in the LED matrix of the light-emitting surface are lightened;

an eighth frame of picture, as shown in FIG. 6H, in which the LEDs of rows **10** to **16** in column **4**, the LEDs of rows **8** to **16** in column **5**, the LEDs of rows **7** to **16** in column **6**, the LEDs of rows **6** to **14** in column **7**, and the LEDs of rows **5** to **12** in column **8** in the LED matrix of the light-emitting surface are lightened;

a ninth frame of picture, as shown in FIG. 6I, in which the LEDs of rows **7** to **16** in column **4**, the LEDs of rows **4** to **16** in column **5**, the LEDs of rows **3** to **15** in column **6**, and the LEDs of rows **3** to **14** in column **7** in the LED matrix of the light-emitting surface are lightened;

a tenth frame of picture, as shown in FIG. 6J, in which the LEDs of rows **10** to **15** in column **4**, the LEDs of rows **7** to **15** in column **5**, the LEDs of rows **6** to **14** in column **6**, the LEDs of rows **3** to **13** in column **7**, and the LEDs of rows **3** to **10** in column **8** in the LED matrix of the light-emitting surface are lightened;

an eleventh frame of picture, as shown in FIG. 6K, in which the LEDs of rows **6** to **15** in column **3**, the LEDs of rows **4** to **15** in columns **4**, **5**, and the LEDs of rows **5** to **14** in column **6** in the LED matrix of the light-emitting surface are lightened;

a twelfth frame of picture, as shown in FIG. 6L, in which the LEDs of rows **8** to **14** in column **3**, the LEDs of rows **2** to **15** in columns **4**, **5**, and the LEDs of rows **4** to **14** in column **6** in the LED matrix of the light-emitting surface are lightened;

a thirteenth frame of picture, as shown in FIG. 6M, in which the LEDs of rows **4** to **15** in column **3**, the LEDs of rows **2** to **16** in columns **4**, **5**, and the LEDs of rows **6** to **13** in column **6** in the LED matrix of the light-emitting surface are lightened;

a fourteenth frame of picture, as shown in FIG. 6N, in which the LEDs of rows **5** to **8** in column **1**, the LEDs of rows **4** to **12** in column **2**, the LEDs of rows **4** to **15** in column **3**, the LEDs of rows **1** to **15** in columns **4**, **5**, and the LEDs of rows **2** to **10** in column **6** in the LED matrix of the light-emitting surface are lightened;

a fifteenth frame of picture, as shown in FIG. 6O, in which the LEDs of rows **3** to **11** in column **2**, the LEDs of rows **1** to **15** in column **3**, the LEDs of rows **2** to **16** in column **4**, and the LEDs of rows **6** to **15** in column **5** in the LED matrix of the light-emitting surface are lightened;

a sixteenth frame of picture, as shown in FIG. 6P, in which the LEDs of rows **2** to **7** in column **1**, the LEDs of rows **3** to **13** in column **2**, the LEDs of rows **4** to **15** in column **3**, the LEDs of rows **6** to **15** in column **4**, and the LEDs of rows **10** to **14** in column **5** in the LED matrix of the light-emitting surface are lightened;

a seventeenth frame of picture, as shown in FIG. 6Q, in which the LEDs of rows **3** to **11** in column **2**, the LEDs of rows **1** to **15** in column **3**, the LEDs of rows **2** to **16** in column **4**, and the LEDs of rows **6** to **15** in column **5** in the LED matrix of the light-emitting surface are lightened;

11

an eighteenth frame of picture, as shown in FIG. 6R, in which the LEDs of rows 7 to 15 in column 3, the LEDs of rows 4 to 16 in column 4, the LEDs of rows 3 to 16 in column 5, the LEDs of rows 3 to 13 in column 6, and the LEDs of rows 4 to 10 in column 7 in the LED matrix of the light-emitting surface are lightened;

a nineteenth frame of picture, as shown in FIG. 6S, in which the LEDs of rows 5 to 14 in column 3, the LEDs of rows 1 to 15 in columns 4, 5, and the LEDs of rows 5 to 13 in column 6 in the LED matrix of the light-emitting surface are lightened;

a twentieth frame of picture, as shown in FIG. 6T, in which the LEDs of rows 6 to 14 in column 3, the LEDs of rows 5 to 15 in column 4, the LEDs of rows 4 to 15 in column 5, and the LEDs of rows 5 to 14 in column 6 in the LED matrix of the light-emitting surface are lightened;

a twenty-first frame of picture, as shown in FIG. 6U, in which the LEDs of rows 6 to 16 in column 4, the LEDs of rows 4 to 16 in column 5, and the LEDs of rows 4 to 15 in column 6 in the LED matrix of the light-emitting surface are lightened;

a twenty-second frame of picture, as shown in FIG. 6V, in which the LEDs of rows 11 to 16 in column 4, the LEDs of rows 8 to 16 in column 5, the LEDs of rows 6 to 15 in column 6, the LEDs of rows 5 to 14 in column 7, and the LEDs of rows 4 to 12 in column 8 in the LED matrix of the light-emitting surface are lightened;

a twenty-third frame of picture, as shown in FIG. 6W, in which the LEDs of rows 10 to 16 in column 4, the LEDs of rows 9 to 16 in column 5, the LEDs of rows 8 to 15 in column 6, the LEDs of rows 8 to 13 in column 7, and the LEDs of rows 9 to 12 in column 8 in the LED matrix of the light-emitting surface are lightened;

a twenty-fourth frame of picture, as shown in FIG. 6X, in which the LEDs of rows 6 to 10 in column 1, the LEDs of rows 6 to 13 in column 2, the LEDs of rows 7 to 16 in columns 3, 4, the LEDs of rows 9 to 16 in column 5, and the LEDs of rows 10 to 16 in column 6 in the LED matrix of the light-emitting surface are lightened; and

a twenty-fifth frame of picture, as shown in FIG. 6Y, in which the LEDs of rows 5 to 15 in column 3, the LEDs of rows 4 to 16 in column 4, the LEDs of rows 5 to 16 in column 5, and the LEDs of rows 6 to 14 in column 6 in the LED matrix of the light-emitting surface are lightened.

As will be appreciated by those skilled in the art, in order to make the electronic candle lamp display a relatively good candlelight effect with flickering flames, preferably each of the light-emitting surfaces circularly displays the aforesaid twenty-five frames of pictures in sequence so that the electronic candle lamp can dynamically and realistically simulate the candlelight effect with flickering flames emitted from a lightened candle.

Of course, as will be appreciated by those skilled in the art, maybe only part of the aforesaid twenty-five frames of pictures are selected and displayed circularly during the displaying of the electronic candle lamp, and this can also simulate the candlelight effect of a lightened candle except that the displaying effect is not so good; or, other pictures may be added to the aforesaid twenty-five frames of pictures to add other special displaying effects.

Moreover, during the displaying, each of the aforesaid twenty-five frames of pictures is displayed for a predetermined period of time, e.g., 100~150 ms, and preferably for 130 ms. Of course, as will be appreciated by those skilled in the art, the aforesaid predetermined period of time may be adjusted depending on practical needs.

12

According to the above descriptions, the LED lamp and the electronic candle lamp of the present disclosure electronically control the LEDs in the plurality of groups of lamp bodies to display the candlelight effect with flickering flames, so a realistic simulation effect is provided; and furthermore, the present disclosure adopts LEDs to replace the traditional candles to emit light, so the lamps of the present disclosure are environment friendly and durable and have a great market.

What described above are only the embodiments of the present disclosure, but are not intended to limit the scope of the present disclosure. Any equivalent structures or equivalent process flow modifications that are made according to the specification and the attached drawings of the present disclosure, or any direct or indirect applications of the present disclosure in other related technical fields shall all be covered within the scope of the present disclosure.

What is claimed is:

1. An electronic candle lamp, comprising:
a baseplate;

a plurality of groups of lamp bodies, disposed on the baseplate, wherein all groups of lamp bodies are connected to a same center, and extend out from the same center, every two adjacent lamp bodies form a predetermined angle therebetween, and each group of the lamp bodies respectively comprises:

a circuit board, disposed vertically on the baseplate;
a first LED matrix, disposed on a first surface of the circuit board; and

a second LED matrix, disposed on a second surface of the circuit board, wherein the first surface is opposite to the second surface;

wherein the first surface of each group of the lamp bodies faces the second surface of an adjacent group of the lamp bodies, and the first LED matrix on the first surface of each group of the lamp bodies and the second LED matrix on the second surface of the adjacent group of the lamp bodies form a light-emitting surface such that at least one whole light-emitting surface is visible at any viewing location;

a lamp shade, disposed on the baseplate and having the plurality of groups of lamp bodies nested therein; and a controlling device, electrically connected to the plurality of groups of lamp bodies, and being configured to control part of the LEDs in each group of the lamp bodies to emit light so that the electronic candle lamp presents a candlelight effect with flickering flames;

wherein each of the first LED matrix and the second LED matrix on the same light-emitting surface is a 4×16 LED matrix respectively, and the first LED matrix and the second LED matrix together form an 8×16 LED matrix;

wherein during the displaying of the electronic candle lamp, images displayed by each light-emitting surface at least comprises some or all of following pictures:
a first frame of picture, in which the LEDs of rows 6 to 14 in column 3, the LEDs of rows 3 to 15 in columns 4, 5, and the LEDs of rows 5 to 13 in column 6 in the light-emitting surface are lightened;

a second frame of picture, in which the LEDs of rows 7 to 13 in column 3, the LEDs of rows 1 to 15 in columns 4, 5, and the LEDs of rows 5 to 14 in column 6 in the light-emitting surface are lightened;

a third frame of picture, in which the LEDs of rows 6 to 12 in column 3, the LEDs of rows 5 to 15 in column 4, the LEDs of rows 3 to 15 in column 5, the LEDs of

13

rows 3 to 13 in column 6, and the LEDs of rows 6 to 11 in column 7 in the light-emitting surface are lightened;

a fourth frame of picture, in which the LEDs of rows 6 to 16 in column 4, the LEDs of rows 4 to 16 in column 5, the LEDs of rows 4 to 14 in column 6, and the LEDs of rows 5 to 12 in column 7 in the light-emitting surface are lightened;

a fifth frame of picture, in which the LEDs of rows 5 to 15 in column 3, the LEDs of rows 5 to 16 in column 4, the LEDs of rows 6 to 16 in column 5, and the LEDs of rows 9 to 14 in column 6 in the light-emitting surface are lightened;

a sixth frame of picture, in which the LEDs of rows 13 to 16 in column 3, the LEDs of rows 12 to 16 in column 4, the LEDs of rows 11 to 16 in columns 5, 6, and the LEDs of rows 12 to 15 in column 7 in the light-emitting surface are lightened;

a seventh frame of picture, in which the LEDs of rows 8 to 16 in columns 4, 5, the LEDs of rows 7 to 15 in column 6, the LEDs of rows 7 to 14 in column 7, and the LEDs of rows 7 to 11 in column 8 in the light-emitting surface are lightened;

an eighth frame of picture, in which the LEDs of rows 10 to 16 in column 4, the LEDs of rows 8 to 16 in column 5, the LEDs of rows 7 to 16 in column 6, the LEDs of rows 6 to 14 in column 7, and the LEDs of rows 5 to 12 in column 8 in the light-emitting surface are lightened;

a ninth frame of picture, in which the LEDs of rows 7 to 16 in column 4, the LEDs of rows 4 to 16 in column 5, the LEDs of rows 3 to 15 in column 6, and the LEDs of rows 3 to 14 in column 7 in the light-emitting surface are lightened;

a tenth frame of picture, in which the LEDs of rows 10 to 15 in column 4, the LEDs of rows 7 to 15 in column 5, the LEDs of rows 6 to 14 in column 6, the LEDs of rows 3 to 13 in column 7, and the LEDs of rows 3 to 10 in column 8 in the light-emitting surface are lightened;

an eleventh frame of picture, in which the LEDs of rows 6 to 15 in column 3, the LEDs of rows 4 to 15 in columns 4, 5, and the LEDs of rows 5 to 14 in column 6 in the light-emitting surface are lightened;

a twelfth frame of picture, in which the LEDs of rows 8 to 14 in column 3, the LEDs of rows 2 to 15 in columns 4, 5, and the LEDs of rows 4 to 14 in column 6 in the light-emitting surface are lightened;

a thirteenth frame of picture, in which the LEDs of rows 4 to 15 in column 3, the LEDs of rows 2 to 16 in columns 4, 5, and the LEDs of rows 6 to 13 in column 6 in the light-emitting surface are lightened;

a fourteenth frame of picture, in which the LEDs of rows 5 to 8 in column 1, the LEDs of rows 4 to 12 in column 2, the LEDs of rows 4 to 15 in column 3, the LEDs of rows 1 to 15 in columns 4, 5, and the LEDs of rows 2 to 10 in column 6 in the light-emitting surface are lightened;

a fifteenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened;

a sixteenth frame of picture, in which the LEDs of rows 2 to 7 in column 1, the LEDs of rows 3 to 13 in column 2, the LEDs of rows 4 to 15 in column 3, the LEDs of

14

rows 6 to 15 in column 4, and the LEDs of rows 10 to 14 in column 5 in the light-emitting surface are lightened;

a seventeenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened;

an eighteenth frame of picture, in which the LEDs of rows 7 to 15 in column 3, the LEDs of rows 4 to 16 in column 4, the LEDs of rows 3 to 16 in column 5, the LEDs of rows 3 to 13 in column 6, and the LEDs of rows 4 to 10 in column 7 in the light-emitting surface are lightened;

a nineteenth frame of picture, in which the LEDs of rows 5 to 14 in column 3, the LEDs of rows 1 to 15 in columns 4, 5, and the LEDs of rows 5 to 13 in column 6 in the light-emitting surface are lightened;

a twentieth frame of picture, in which the LEDs of rows 6 to 14 in column 3, the LEDs of rows 5 to 15 in column 4, the LEDs of rows 4 to 15 in column 5, and the LEDs of rows 5 to 14 in column 6 in the light-emitting surface are lightened;

a twenty-first frame of picture, in which the LEDs of rows 6 to 16 in column 4, the LEDs of rows 4 to 16 in column 5, and the LEDs of rows 4 to 15 in column 6 in the light-emitting surface are lightened;

a twenty-second frame of picture, in which the LEDs of rows 11 to 16 in column 4, the LEDs of rows 8 to 16 in column 5, the LEDs of rows 6 to 15 in column 6, the LEDs of rows 5 to 14 in column 7, and the LEDs of rows 4 to 12 in column 8 in the light-emitting surface are lightened;

a twenty-third frame of picture, in which the LEDs of rows 10 to 16 in column 4, the LEDs of rows 9 to 16 in column 5, the LEDs of rows 8 to 15 in column 6, the LEDs of rows 9 to 12 in column 8 in the light-emitting surface are lightened;

a twenty-fourth frame of picture, in which the LEDs of rows 6 to 10 in column 1, the LEDs of rows 6 to 13 in column 2, the LEDs of rows 7 to 16 in columns 3, 4, the LEDs of rows 9 to 16 in column 5, and the LEDs of rows 10 to 16 in column 6 in the light-emitting surface are lightened; and

a twenty-fifth frame of picture, in which the LEDs of rows 5 to 15 in column 3, the LEDs of rows 4 to 16 in column 4, the LEDs of rows 5 to 16 in column 5, and the LEDs of rows 6 to 14 in column 6 in the light-emitting surface are lightened;

wherein each light-emitting surface circularly displays the first frame of picture to the twenty-fifth frame of picture in sequence, so that the electronic candle lamp dynamically displays the candlelight effect with flickering flames.

2. The electronic candle lamp of claim 1, comprising three groups of the lamp bodies, and every two adjacent lamp bodies form an angle of 120 degrees therebetween.

3. The electronic candle lamp of claim 1, wherein each of the first frame of picture to the twenty-fifth frame of picture is displayed for 100~150 ms.

4. The electronic candle lamp of claim 1, wherein the controlling device comprises a controller and a plurality of controlling circuits, the controller is electrically connected to the plurality of controlling circuits to input instructions to each of the controlling circuits, and each of the controlling circuits is electrically connected to the first LED matrix and

15

the second LED matrix on a corresponding group of the lamp bodies, or connected to the first LED matrix and the second LED matrix on a same light-emitting surface, to control the LEDs on each group of the lamp bodies or on each light-emitting surface so that the electronic candle lamp displays the candlelight effect with flickering flames.

5. A light-emitting diode (LED) lamp, comprising:

a baseplate;

a plurality of groups of lamp bodies, disposed on the baseplate, wherein all groups of lamp bodies are connected to a same center, and extend out from the same center, and every two adjacent lamp bodies form a predetermined angle therebetween; and each group of the lamp bodies respectively comprises:

a circuit board, disposed vertically on the baseplate; 10 a first LED matrix, disposed on a first surface of the circuit board; and

a second LED matrix, disposed on a second surface of the circuit board, wherein the first surface is opposite to the second surface;

wherein the first surface of each group of the lamp bodies faces the second surface of an adjacent group of the lamp bodies, and the first LED matrix on the first surface of each group of the lamp bodies and the second LED matrix on the second surface of the adjacent group of the lamp bodies form a light-emitting surface such that at least one whole light-emitting surface is visible at any viewing location;

a lamp shade, disposed on the baseplate and having the plurality of groups of lamp bodies nested therein; and a controlling device, electrically connected to the plurality 30

of groups of lamp bodies to control part of the LEDs in each group of the lamp bodies to emit light so that the LED lamp presents light-emitting effects of various forms;

wherein each of the first LED matrix and the second LED matrix on the same light-emitting surface is a 4×16 LED matrix respectively, and the first LED matrix and the second LED matrix together form an 8×16 LED matrix;

wherein during the displaying of the LED lamp, images displayed by each of the light-emitting surfaces at least comprises some or all of following pictures:

a first frame of picture, in which the LEDs of rows 6 to 45 14 in column 3, the LEDs of rows 3 to 15 in columns 4, 5, and the LEDs of rows 5 to 13 in column 6 in the light-emitting surface are lightened;

a second frame of picture, in which the LEDs of rows 7 to 50 13 in column 3, the LEDs of rows 1 to 15 in columns 4, 5, and the LEDs of rows 5 to 14 in column 6 in the light-emitting surface are lightened;

a third frame of picture, in which the LEDs of rows 6 to 55 12 in column 3, the LEDs of rows 5 to 15 in column 4, the LEDs of rows 3 to 15 in column 5, the LEDs of rows 3 to 13 in column 6, and the LEDs of rows 6 to 11 in column 7 in the light-emitting surface are lightened;

a fourth frame of picture, in which the LEDs of rows 6 to 60 16 in column 4, the LEDs of rows 4 to 16 in column 5, the LEDs of rows 4 to 14 in column 6, and the LEDs of rows 5 to 12 in column 7 in the light-emitting surface are lightened;

a fifth frame of picture, in which the LEDs of rows 5 to 65 15 in column 3, the LEDs of rows 5 to 16 in column 4, the LEDs of rows 6 to 16 in column 5, and the LEDs of rows 9 to 14 in column 6 in the light-emitting surface are lightened;

16

a sixth frame of picture, in which the LEDs of rows 13 to 16 in column 3, the LEDs of rows 12 to 16 in column 4, the LEDs of rows 11 to 16 in columns 5, 6, and the LEDs of rows 12 to 15 in column 7 in the light-emitting surface are lightened;

a seventh frame of picture, in which the LEDs of rows 8 to 16 in columns 4, 5, the LEDs of rows 7 to 15 in column 6, the LEDs of rows 7 to 14 in column 7, and the LEDs of rows 7 to 11 in column 8 in the light-emitting surface are lightened;

an eighth frame of picture, in which the LEDs of rows 10 to 16 in column 4, the LEDs of rows 8 to 16 in column 5, the LEDs of rows 7 to 16 in column 6, the LEDs of rows 6 to 14 in column 7, and the LEDs of rows 5 to 12 in column 8 in the light-emitting surface are lightened;

a ninth frame of picture, in which the LEDs of rows 7 to 16 in column 4, the LEDs of rows 4 to 16 in column 5, the LEDs of rows 3 to 15 in column 6, and the LEDs of rows 3 to 14 in column 7 in the light-emitting surface are lightened;

a tenth frame of picture, in which the LEDs of rows 10 to 15 in column 4, the LEDs of rows 7 to 15 in column 5, the LEDs of rows 6 to 14 in column 6, the LEDs of rows 3 to 13 in column 7, and the LEDs of rows 3 to 10 in column 8 in the light-emitting surface are lightened;

an eleventh frame of picture, in which the LEDs of rows 6 to 15 in column 3, the LEDs of rows 4 to 15 in columns 4, 5, and the LEDs of rows 5 to 14 in column 6 in the light-emitting surface are lightened;

a twelfth frame of picture, in which the LEDs of rows 8 to 14 in column 3, the LEDs of rows 2 to 15 in columns 4, 5, and the LEDs of rows 4 to 14 in column 6 in the light-emitting surface are lightened;

a thirteenth frame of picture, in which the LEDs of rows 4 to 15 in column 3, the LEDs of rows 2 to 16 in columns 4, 5, and the LEDs of rows 6 to 13 in column 6 in the light-emitting surface are lightened;

a fourteenth frame of picture, in which the LEDs of rows 5 to 8 in column 1, the LEDs of rows 4 to 12 in column 2, the LEDs of rows 4 to 15 in column 3, the LEDs of rows 1 to 15 in columns 4, 5, and the LEDs of rows 2 to 10 in column 6 in the light-emitting surface are lightened;

a fifteenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened;

a sixteenth frame of picture, in which the LEDs of rows 2 to 7 in column 1, the LEDs of rows 3 to 13 in column 2, the LEDs of rows 4 to 15 in column 3, the LEDs of rows 6 to 15 in column 4, and the LEDs of rows 10 to 14 in column 5 in the light-emitting surface are lightened;

a seventeenth frame of picture, in which the LEDs of rows 3 to 11 in column 2, the LEDs of rows 1 to 15 in column 3, the LEDs of rows 2 to 16 in column 4, and the LEDs of rows 6 to 15 in column 5 in the light-emitting surface are lightened;

an eighteenth frame of picture, in which the LEDs of rows 7 to 15 in column 3, the LEDs of rows 4 to 16 in column 4, the LEDs of rows 3 to 16 in column 5, the LEDs of rows 3 to 13 in column 6, and the LEDs of rows 4 to 10 in column 7 in the light-emitting surface are lightened;

17

a nineteenth frame of picture, in which the LEDs of rows **5** to **14** in column **3**, the LEDs of rows **1** to **15** in columns **4**, **5**, and the LEDs of rows **5** to **13** in column **6** in the light-emitting surface are lightened;

a twentieth frame of picture, in which the LEDs of rows **6** to **14** in column **3**, the LEDs of rows **5** to **15** in column **4**, the LEDs of rows **4** to **15** in column **5**, and the LEDs of rows **5** to **14** in column **6** in the light-emitting surface are lightened;

a twenty-first frame of picture, in which the LEDs of rows **6** to **16** in column **4**, the LEDs of rows **4** to **16** in column **5**, and the LEDs of rows **4** to **15** in column **6** in the light-emitting surface are lightened;

a twenty-second frame of picture, in which the LEDs of rows **11** to **16** in column **4**, the LEDs of rows **8** to **16** in column **5**, the LEDs of rows **6** to **15** in column **6**, the LEDs of rows **5** to **14** in column **7**, and the LEDs of rows **4** to **12** in column **8** in the light-emitting surface are lightened;

a twenty-third frame of picture, in which the LEDs of rows **10** to **16** in column **4**, the LEDs of rows **9** to **16** in column **5**, the LEDs of rows **8** to **15** in column **6**, the LEDs of rows **8** to **13** in column **7**, and the LEDs of rows **9** to **12** in column **8** in the light-emitting surface are lightened;

5

10

15

20

18

a twenty-fourth frame of picture, in which the LEDs of rows **6** to **10** in column **1**, the LEDs of rows **6** to **13** in column **2**, the LEDs of rows **7** to **16** in columns **3**, **4**, the LEDs of rows **9** to **16** in column **5**, and the LEDs of rows **10** to **16** in column **6** in the light-emitting surface are lightened; and

a twenty-fifth frame of picture, in which the LEDs of rows **5** to **15** in column **3**, the LEDs of rows **4** to **16** in column **4**, the LEDs of rows **5** to **16** in column **5**, and the LEDs of rows **6** to **14** in column **6** in the light-emitting surface are lightened;

wherein each light-emitting surface circularly displays the first frame of picture to the twenty-fifth frame of picture in sequence, so that the LED lamp dynamically displays the candlelight effect with flickering flames.

6. The LED lamp of claim **5**, wherein the LEDs in both the first LED matrix and the second LED matrix of each group of the lamp bodies are LED chips, and the LED chips in the first LED matrix and/or the second LED matrix are integrally encapsulated on the first surface and/or the second surface.
